Atlys.

UNITED STATES PATENT OFFICE.

JOHN JAMES McCANN, OF CHICAGO, ILLINOIS.

PRAYER RAIL.

Application filed November 5, 1923. Serial No. 672,757.

This invention relates to improvements in prayer rails. It is particularly directed to improvements over the construction shown and described in my U. S. Letters Patent No. 1,394,919, issued October 25, 1921.

The invention in the present instance is particularly useful to undertakers for use in connection with funeral rites conducted and observed by people under the Roman Catholic faith at funeral wakes.

The invention is particularly useful in eliminating the embarrassing difficulties met in the performance of such funeral rites in the observance of prayer before the casket of the deceased by the provision of a prayer rail, which will enable persons kneeling before the casket to do so with great ease, and provide means for enabling them to arise with the least possible effort and inconvenience.

One of the objects of the present invention is to provide an improved collapsible prayer rail which can be readily knocked down by the undertaker and be compactly arranged in a container, such, for instance, as an ordinary suitcase, for convenient transportation from place to place.

A further object of the invention is to provide an improved prayer rail which is strong and durable in construction, and which, at the same time, is light in weight.

A still further object of the invention is to provide an improved means for detachably and frictionally securing the parts together which go to make up the prayer rail.

A still further object of the invention is to provide a supplemental detachable support between the two sections of the kneeling bench.

These and other objects are accomplished by providing a constructional arrangement of the various parts in the manner herein-after described, and particularly pointed out in the appended claims.

Referring to the drawings—

Figure 1 is a front elevational view of my improved form of prayer rail;

Fig. 2 is a side elevational view of the end bracket;

Fig. 3 is a side elevational view of the detachable supplemental support for supporting the inner ends of the sections which go to make up the kneeling bench;

Figs. 4 and 5 are side elevational views and bottom plan views respectively of the pins by means of which the sections are adapted

to be detachably secured to the end brackets and supplemental intermediate support;

Fig. 6 is a fragmentary cross-sectional view showing the manner in which the cross rail is detachably secured to the end brackets; and

Fig. 7 is a fragmentary cross-sectional view showing the manner in which the sections which go to make up the cross-rail are frictionally secured together.

In carrying out the present invention, I have shown my improved prayer rail as comprising end brackets 10, which are adapted to rest on the floor, and are preferably made of aluminum so as to be light in structure. These end brackets are substantially L-shape in form, and are provided at their upper ends thereof with vertical sockets 11, which are formed integrally therewith. The vertical sockets 11 are provided with a thumb screw adjustment 12 for the purpose herein-after set forth. The lower end of the brackets 10 are provided with inwardly extending shoulders 13. These shoulders 13 are provided with vertically extending apertures 14.

In order to make my improved rail collapsible so that the same can be compactly arranged so as to occupy a minimum amount of space and be conveniently carried in a container, such, for instance, as an ordinary suitcase, I have provided a kneeling rail comprising two sections, as shown at 15, which are preferably upholstered on the top side thereof. The outer ends of these brackets are provided with frictional slip connections comprising a plurality of pins 16, which are adapted to engage the apertures 14 in the outer brackets by being frictionally secured therein, as clearly shown in Fig. 1.

In order to support the inner ends of these sections 15, I have provided an intermediate or supplemental support 17, which comprises a base 18 and an upper plate 19. The upper plate 19 is provided with a plurality of apertures 20, which are adapted to have frictionally secured therein the pins 16 secured to the inner ends of the sections 15 of the bench, as clearly shown in Figs. 1 and 3.

The upper ends of the end brackets 10 are held rigidly in their respective positions after the rail has been assembled by a cross-rail 21, which is made up of two sections 22. These sections 22 are frictionally secured together by a collar 23. The outer ends of the rail sections 22 have formed integrally there-

with knobs 24, which, in turn, have formed integrally vertically extending portions 25. These vertical portions 25 of the rails 22 are adapted to telescopically connect with the 5 vertical sockets 11 formed in the end brackets 10. The height of the cross-rail may be adjusted with respect to the end rails by adjusting the vertical portion 25 of the sections 22 in the sockets 11 of the brackets 10 by the 10 thumb screw 12, which is adapted to engage a plurality of apertures 26 formed in these vertical portions.

From the above description it will be seen that when the sections 22, together with their 15 vertical portions 25 which go to make up the cross-rail 21, are withdrawn from the sockets 11 that these sections may be disconnected from the collar 23, and that the sections 15 which go to make up the kneeling bench are disconnected from the end brackets and intermediate support that all these parts which go to make up my collapsible prayer rail may be arranged so as to occupy a minimum 20 amount of space in order that the same may be conveniently transported in a container of substantially the same size as an ordinary suitcase.

When the device is assembled it is placed before the casket, and persons offering prayer 30 may rest their hands upon the rail to enable them to assume a kneeling position on the bench, and when rising may use the rail to assist them to assume a standing position without difficulty or discomfort.

From the above description it will be noted 35 that I have provided a very simple and efficient prayer rail construction which has substantially all of its parts frictionally secured together, by reason of which the same 40 can be readily knocked down and compactly arranged so that the same can be conveniently transported from place to place.

What I claim as my invention and desire 45 to secure by Letters Patent is:

1. A collapsible prayer rail comprising 50 a pair of end brackets, a sectional kneeling bench detachably secured adjacent the lower end of and supported on said brackets, a supplemental support adapted to rest on the floor and engage the inner ends of said sections, and a cross-rail detachably secured to the upper ends of said brackets for rigidly securing said brackets together.

2. A collapsible prayer rail comprising 55 a pair of end brackets adapted to rest on the floor, a sectional kneeling bench mounted on said brackets, a supplemental support mounted between said brackets for supporting the inner ends of said sectional kneeling bench, means for frictionally securing said kneeling bench to said brackets and supplemental support comprising vertically extending pins and cooperating sockets therefor, a cross rail connecting the upper 60 ends of said brackets together and means

for frictionally securing said cross rails to said brackets.

3. A collapsible prayer rail comprising a pair of end brackets, a sectional kneeling bench detachably secured by means of frictional connections to said brackets, a supplemental support adapted to rest on the floor and detachably connected to said sections at the junction of said sections by means of frictional slip connections, and a 70 cross-rail for detachably securing said brackets rigidly together.

4. A collapsible prayer rail comprising a pair of end brackets, a kneeling bench made up of two sections, a supplemental vertical 80 support positioned between said brackets and adapted to rest on the floor and support the inner ends of said sections, the latter being secured by means of frictional connections to said supplemental support and a 85 cross rail being frictionally secured to the upper ends of said brackets for rigidly securing said brackets together.

5. A collapsible prayer rail comprising a pair of end brackets, a kneeling bench comprising a plurality of sections mounted on said brackets, there being a plurality of apertures in said brackets, a plurality of pins carried on the inner and outer ends of said sections, the pins on the outer ends of said 90 sections engageable with the apertures in said brackets for detachably securing said sections to said brackets, a supplemental support adapted to rest on the floor and positioned adjacent the inner ends of said sections, said support having a plurality of apertures adapted to receive the pins on the inner ends of said sections, and a sectional cross-rail detachably secured to said brackets for rigidly securing said brackets together.

6. A knock-down prayer rail of sectional character comprising a tubular sectional arm rest, a sectional knee rest, detachable end brackets therefor detachably connected respectively to a corresponding section of the arm rest and knee rest sections, and a detachable middle support formed and adapted to connect and support the adjacent ends of the knee rest sections, the arm rest sections being connected by a splice member concentric with the arm rest sections which abut together endwise.

7. A collapsible prayer rail comprising a pair of end brackets, an arm rest consisting of a plurality of sections connected to the upper ends of said brackets, a knee rest consisting of a plurality of sections mounted on said brackets, and means for securing the inner ends of said knee rest sections together.

8. A collapsible prayer rail comprising a pair of end brackets, said prayer rail being substantially twice as long as high, an arm rest consisting of a plurality of sections connected to the upper ends of said bracket,

a knee rest consisting of a plurality of sections mounted on said bracket, and means for securing the inner ends of said knee rest sections together.

5 9. A collapsible prayer rail comprising a pair of end brackets, an arm rest consisting of a plurality of sections connected to the upper ends of said brackets, a knee rest consisting of a plurality of sections mounted on

said brackets, and means mounted on the 10 under side of and adjacent the inner ends of said knee rest sections for securing said sections together.

In testimony whereof I have signed my name to this specification, on this 20th day 15 of October A. D. 1923.

JOHN JAMES McCANN.
